FINGER RING

Moe Manne, New York, N. Y.

Application December 16, 1944, Serial No. 568,441

4 Claims. (Cl. 63—15)

This invention relates to finger rings and similar articles and has for its primary object the provision of a ring of novel construction, lending itself to the production of many handsome and artistic designs and adaptations following from a basic structure of a ring body which is so arranged that simplicity of manufacture of rings in many different designs is possible.

More particularly, the invention contemplates the provision of a ring body or annulus which is longitudinally split for the greater portion of its circumference or length to provide a plurality of divergent or spread segments or arcuate jaws between which settings, ornaments, mountings and other design elements may be mounted and assembled to co-operate with the jaws or segments in providing rings of various kinds and designs.

Another object of the invention is to provide a basic type of ring body which will, without material change in structure, serve as the foundation or base for the production of wedding rings, engagement rings and a multitude of rings of other design, thus greatly simplifying the work of the jeweler, yet providing for the purchaser many artistic ring designs.

In the accompanying drawing, wherein an illustrative embodiment of the invention is shown, Fig. 1 is a front elevation of a ring body constructed in accordance with the invention; Fig. 2 is a side elevation of the same; Fig. 3 is a front view of a ring in which the body of Figs. 1 and 2 has been utilized; Fig. 4 is a transverse sectional view through a ring body of the improved construction and a setting mounted therein; Fig. 5 is a front elevation of a slightly modified structure, and Fig. 6 is a side elevation of a ring such as shown in Fig. 5.

Referring to the drawing, 1 indicates the shank portion of a finger ring body of annular form. The same is split longitudinally as indicated at 2 to thereby form it into the two parts or jaws 3 and 4. The split 2 is of considerable length and is usually more than one-half of the circumference of the body of the ring. The parts or jaws 3 and 4 are thus segments of arcuate form and are spread apart to extend divergently from the base 10 of the split 2, thus providing a substantially V-shaped or "clam-shell" opening between them when the ring body is viewed edgewise, or as in Figs. 2 and 6.

It will be noted that the inner surfaces of the jaws or segments 3 and 4, or those surfaces which face one another, and are indicated at 5, are inclined or angularly disposed, and these angular surfaces co-operate in the formation of a taper-

ing seat or support for the reception of a mounting, setting, ornament or other elements co-operating with the body of the ring to form many ornamental designs and ring types. For example, in Figs. 3 and 4 is shown a multiple setting 6 placed between the angular surfaces 5 of the segments or jaws 3 and 4 and secured to said surfaces by being soldered thereto so that the setting 6, containing gems 7, extends between and is supported by the segments or jaws 3 and 4 and thus bridges the space therebetween.

When a setting is mounted in the manner described, and is thus firmly secured between the two segments or jaws 3 and 4, the inwardly-facing angular surfaces 5, which are highly polished, tend by reflection, to greatly enhance the brilliancy of the mounted gems. Moreover, mounting of the setting between the segments or jaws 3 and 4 in the manner explained, allows the jeweler considerable latitude in construction, since the angular surfaces 5 readily permit the setting or other ornament to be mounted in a raised or high position or in a low position or at any point desired, by merely bringing the segments or jaws 20 to or from one another to the extent required, the malleability of the metal of the ring body and the relatively great length of the split 2 readily permitting such an adjustment. Thus, it is simple for the jeweler to produce a "high" or "low" 25 setting merely by placing the setting at the point between the jaws or segments as required to secure the desired effect.

It will be clear that a ring body of the construction described will permit the production of 30 a very large number of radically different ring designs, yet all of which will be based upon a ring body of the type described. By mounting various types of settings and ornaments between the segments or jaws 3 and 4 and by locating 35 these segments at the desired distance apart, or at the desired "spread," engagement rings, wedding rings, men's and women's rings of many designs can be produced. Large and small stones and combinations of stones of various shapes and 40 sizes, and one or more rows of small stones, and many other stone arrangements can be readily set in position between the segments to secure different design effects. In making the ring body and fitting settings or ornaments between the segments or jaws 3 and 4, these segments or jaws 45 can be sprung to or from one another when necessary to insure proper fit and elevation of the ornaments or settings to be placed between them, whereupon the parts are soldered in position.

50 While the ornaments or settings placed be-

55

tween the two segments or jaws can be readily solely supported by the same, in some cases additional struts, such as shown at 9, and extending from the base of the split 2 can meet the ends of the ornament or setting and not only materially brace the same, but add to and enhance the design, as shown in Figs. 5 and 6. Various other modifications are readily made, since a great deal of latitude in the production of rings of various forms is possible by the use of the basic ring body herein described.

While I have herein described the device as a finger ring, it will be obvious that the invention need not be so limited since bracelets and other ornamental annuli might well be made in accordance with the invention without departing from the spirit thereof.

What I claim is:

1. A finger ring or other ornamental annulus having a body portion split longitudinally for the greater part of its length to form a top portion composed of two spaced arcuate jaws, each of said jaws having an angular inside surface whereby said surfaces form a diverging seat for

settings or the like adapted to be inserted between the sections and secured to the angular surfaces thereof.

5 2. A finger ring or other ornamental annulus as called for in claim 1, wherein the split in the body portion extends for more than one-half of the circumference of said body portion, and the two arcuate sections diverge from the ends of the split.

10 3. A finger ring or other ornamental annulus having a body portion that is split longitudinally on a substantially central line for more than one-half of its circumference to provide a pair of segments which diverge outwardly from the ends of the split and which are provided with inside angular polished faces, and at least one ornament or setting resting between the inside, angular polished surfaces of the segments.

15 4. A finger ring or other ornamental annulus as called for in claim 3, wherein a supporting strut extends from the ends of the split and joins the ends of the ornament or setting on the central line of the body portion.

MOE MANNE.
